CLAIM

We claim the ornamental design for a shoe, as shown and described.

DESCRIPTION

FIG. 1 is a top-right side perspective view of a shoe, showing our new design.

FIG. 2 is a right side view of the shoe.

FIG. 3 is a left side view of the shoe.

FIG. 4 is a front-bottom perspective view of the shoe.

FIG. 5 is a rear view of the shoe.

FIG. 6 is a top view of the shoe.

FIG. 7 is a bottom view of the shoe; and,

FIG. 8 is a bottom perspective view of the shoe.

The broken lines encircling visible portions of the interior of the shoe define the bounds of the claimed design and form no part thereof.

1 Claim, 7 Drawing Sheets
